UNITED STATES PATENT OFFICE.

ALBERT B. FRENIER, OF DAVENPORT, IOWA.

WHEELED PLOW.

No. 853,448.

Specification of Letters Patent.

Patented May 14, 1907.

Application filed December 17, 1903. Serial No. 185,470.

To all whom it may concern:

Be it known that I, ALBERT B. FRENIER, a citizen of the United States of America, and a resident of Davenport, Scott county, Iowa, have invented a certain new and useful Improvement in Wheeled Plows, of which the following is a specification.

My invention relates to wheeled-plows, and more particularly to wheeled-plows of that type in which a special frame or body is provided, and in which this frame is mounted on wheels and shiftingly connected with the plow-beam, whereby it is not only possible to raise and lower or adjust the frame relatively to the wheels, but also to raise and lower the plow relatively to the frame and the wheels.

Generally stated, the object of my invention is to provide improved means for raising and lowering the plow, and to thereby facilitate the adjustment of the plow relatively to the frame and wheels.

A special object is to provide a construction and mode of operation whereby the two foot-levers may be mounted separately on two separate and distinct movable or oscillatory members, whereby one foot-lever and the member upon which it is mounted can be moved or adjusted without moving or adjusting the other member and its allotted foot-lever, and whereby a lost-motion connection may be employed between the said oscillatory parts upon which the two foot-levers are mounted, said lost-motion connection permitting a spring to be advantageously employed for both assisting in lifting the plow and yieldingly holding the plow in the ground, and permitting the oscillatory member upon which the depressing foot-lever is mounted to have more or less adjustment independently of the other member, for the purpose of bringing the spring from a depressing to a lifting position, and vice versa, and also permitting an adjustment of a locking element, which is rigid with the depressing lever, and which constitutes part of a locking device for locking the plow in an elevated position, without communicating any positive thrust or downward pressure to the plow through the lifting and lowering connection, which latter is preferably a jointed or toggle-like connection.

It is also an object to provide certain details and features of improvement tending to increase the general efficiency and service-

ability of a foot-lifting and lowering device of this particular character.

In the accompanying drawings,—Figure 1 is a side elevation of a wheeled-plow embodying the principles of my invention, the plow being shown in its lowered or working position; Fig. 2 is a view similar to Fig. 1, but showing the front and rear furrow-wheels and certain other parts removed, and showing the plow in elevated or partially elevated position; Fig. 3 is an enlarged plan view of my improved foot-lifting and lowering device, the parts being shown in positions corresponding to the positions in which they are shown in Fig. 1; Fig. 4 is a detail view of the land side of the arrangement shown in Fig. 3, and on the same scale as said figure; Fig. 5 is a view similar to Fig. 4, but showing the plow-beam in an elevated position.

As thus illustrated, my wheeled-plow may comprise a plow A and a plow-beam B of any suitable known or approved form. The horizontally disposed body-frame C, carried by the front and rear furrow-wheels D and E, and the relatively large land-side wheel F, can also be of any suitable form or construction. As illustrated, the plow is swingingly or adjustably hung from the body-frame by means of bails G and G', which have their rear end portions mounted in suitable bearings g and g', carried by the body-frame, and which have their forward and transverse middle portions mounted to turn in suitable castings or bearings g² and g³ secured to the plow-beam. Thus the forward and middle portions of these bails are adapted to swing up and down relatively to the body-frame, and to thereby serve as the shifting connections or means by which the plow is adapted to be raised and lowered relatively to the balance of the structure. In rising, the plow moves upward and slightly to the rear; on the other hand, in descending, the plow moves downward and slightly forward. The rear furrow-wheel D is preferably in the nature of a caster-wheel, having its stem adapted to turn in a bearing or bracket d secured to the rear of the body-frame. Preferably, the forward furrow wheel E is of a similar character, its stem being adapted to turn in a bearing or bracket e secured to the right-hand side of the forward portion of the body-frame. As illustrated, there is, however, a difference between the forward and rear furrow wheels, inasmuch as the bearing e is

adapted to slide up and down upon the stem of the forward furrow wheel, thereby permitting the forward portion of the body frame to be raised and lowered relatively to the forward furrow wheel. This can be accomplished in any suitable manner, as, for example, by pivoting a hand-lever H to the said bracket or bearing e, and by connecting this hand-lever with a casting or bracket h on the upper end of the forward furrow wheel stem, which latter can be connected with the tongue 1. For example, the connection between the lever H and the bracket h may consist of a link h', the same being connected and arranged in any suitable or desired manner. With this provision, it is obvious that a downward swing of the lever H will raise the body-frame, while a reverse motion of the lever will lower the body-frame relatively to the forward furrow wheel.

If desired, the stems of the two furrow-wheels can be connected by a rod J, in any known or approved manner, so that the rear furrow wheel stem will be held against turning while the plow is running straight ahead, but will be free to turn or caster freely when the tongue is swung to one side. The land-side wheel F can be mounted on the spindle or end of the crank-arm of a transversely disposed crank-axle K, which latter is mounted for rocking or oscillatory adjustment in bearings k and k' secured to the body frame. The means for rocking this crank-axle, in the usual and well-known manner, for the purpose of raising and lowering the body-frame or swinging or throwing the plow out of the ground, may consist of a hand-lever L, mounted loosely upon the said crank-axle, but having a yielding or resilient connection with the said axle through the medium of the spring l and the arm l', which latter is secured rigidly to the said axle; it being observed that this spring is arranged for compression between the said arm and a part connected with the said lever. With this arrangement, the land-side wheel F may be said to have a yielding or resilient connection with the body-frame, and in this way a cushioning effect is given to said wheel, when the locking device l² on the said lever is in engagement with the toothed rack l³, which latter is rigid with the bearing k'. A spring l⁴, connected between the upper end portion of the lever L and the said toothed rack l³, is employed as a means for assisting in lifting or changing the level of the body-frame.

With the provision of the two hand-levers H and L, it will be seen that both the forward furrow wheel and land side wheel can be controlled independently of each other and at will, so as to raise and lower the body-frame and wing or manipulate the plow in the usual and well known manner. And at this juncture it will also be observed that the le-

ver H is preferably provided with the locking device h², whereby said lever can be locked in engagement with the rack h³, which latter is secured to the casting or bracket bearing e. The rear portion of the body-frame can be provided with the usual driver's seat M, as shown in Figs. 1 and 2.

The features thus far described can, as stated, be of any suitable known or approved construction, inasmuch as my invention does not relate to these features, and a further description of the same is therefore unnecessary.

It is the double foot-lever arrangement for raising and lowering the plow—that is to say, for adjusting the plow relatively to the body-frame—which constitutes my invention. This improved foot-lever arrangement with its spring for assisting in lifting the plow and for yieldingly maintaining the plow in the ground, so as to permit the plow to operate as a stone dodger, and to thereby avoid danger of breakage by rising over obstructions, is more clearly shown by Figs. 3, 4 and 5. It will be seen that two separate and distinct oscillatory members N and O are carried by the frame, and, if so desired, are conveniently mounted upon the crank-axle K. The member N is provided with a rearwardly projecting lifting foot-lever P, which preferably swings just outside of the body-frame C. In a similar manner, the other member O is provided with an upwardly and forwardly projecting depressing lever Q, which can be arranged over, or substantially over, the plow-beam. It is by thus mounting the two foot-levers separately—that is to say, on two separate and distinct mountings, which, as is readily apparent, can, as a matter of convenience, be in the form of two separate and distinct sleeves mounted on the crank-axle—that the necessary relative movement or independence is secured between the two foot-levers. These two structurally separate elements, N and O, are loosely mounted upon the axle K, and are thus adapted for rocking or oscillatory adjustment thereon. The member N is provided with an arm n, the free end of which is connected with the plow-beam by means of the link n'. The arm n can be provided with an adjustable stop n², whereby the toggle-like lifting and lowering device thus provided can only break joint in an upward direction, and whereby the joint or pivotal connection may be prevented from passing below the center; and, in fact, as will hereinafter more fully appear, it is preferable that the said stop be so adjusted that the joint or pivotal connection n² remains, when the plow is in the ground, a slight distance above a line drawn from the center of the crank-axle through the axis of the pivotal point n⁴.

The member O is preferably provided with a hook o, adapted, when the plow is raised

from the ground, to engage a lug o' on the plate o^2 ; and at this juncture it will be observed that this plate o^2 is preferably adjustably mounted on the plow-beam, thereby making it possible to adjust the parts accurately and in such manner as to insure the desired mode of operation. The adjustability of the said plate can be obtained by providing it with slots x for the attaching bolts o^3 , as shown more clearly in Fig. 4.

In addition to the rigid locking projection or hook o , the member O is also provided with a rigid arm o^4 , to the end of which is attached the bent link or connecting member o^5 . The other end of this link o^5 is connected with one end of a heavy coil-spring R , and the other end of this spring is attached to the forward portion of the body-frame, as, for example, in the manner shown at r in Fig. 1. This spring, thus combined with the two separately mounted foot-levers, as will herein-after more fully appear, is a combined lifting and depressing spring.

There is preferably a lost-motion connection between the two separately mounted foot-levers, said lost motion connection consisting, for example, of a notch n^5 in the sleeve or member N , adapted to engage the tooth o^6 on the other sleeve or member O . By reason of the said notches being considerably larger than the said teeth, the foot-lever Q is capable of considerable manipulation, as will be seen, without communicating any of the pressure or power applied to it to the plow, or to the member N .

The mode of operation is obvious. Suppose it is desired to raise the plow—that is to say, to adjust the plow relatively to the body-frame—from the position shown in Fig. 4. This can be accomplished by simply placing the foot on the lever P , and by then pressing downward, so as to utilize this lever and the arm n as an intermediately fulcrumed lever for lifting the plow through the medium of the connecting link n' . It will be seen, however, that with the parts in the position shown in Fig. 4, the spring R is exerting a pull above the axis of the two levers, and that at this time, therefore, the spring is serving to yieldingly hold the plow in the ground. It is evident, therefore, that should the plow strike a stone or other obstruction, in such case the connections will yield and allow the plow to automatically rise over such obstruction, thereby insuring against breakage or other danger to the structure. But now, as soon as pressure is applied, in the manner stated, to the lever P , the arm o^4 is thrown downward, thereby shifting the spring to a position to pull below the axis of the two foot levers; and, by reason of the lost motion connection between the two sleeves and the two separately mounted foot-levers, there is a substantial lost-motion action on the part of the spring and the various

connections as soon as the point of pivotal connection between the link o^5 and the arm o^4 reaches a point slightly below the axis of the two levers. Thus, as soon as the spring is shifted to a point where it begins to pull slightly below the axis of the two levers, there then takes place a free relative rotation between the two sleeves N and O , resulting in a sudden and forcible shifting of the arm o^4 to a point where the tension or contracting power of the spring can be instantly and advantageously exerted in a direction to assist the foot-lever P in lifting the plow. In other words, it is only necessary for the foot-lever P to be moved slightly, and to an extent to bring the pivotal point o^7 just below the axis of the two foot-levers, in order to permit the spring to automatically adjust itself and its various connections in such manner as to at once avail itself of a substantial and considerable leverage for assisting in raising the plow. In this way, the spring and the lever P co-operate in lifting the plow-beam into the position shown in Fig. 5. In this position, the lug o' carried by the plow-beam engages the hook or locking projection o , which latter is rigid with the depressing lever Q , and is thus mounted separately and independently of the lifting lever P . The plow tends to remain locked in this position, owing to the engagement of the said hook with the lug on the plow-beam, as the plow cannot move downward without first moving forward. It is evident, therefore, that the weight of the plow is exerted in a downward and forward thrust of the lug o' on the hook-shaped end portion of the locking projection o ; it being observed that the point of connection between the bail G and the plow-beam, the cranked or land-side axle K and the point of engagement between the locking elements o and o' , are, when the plow is raised, as shown in Fig. 5, very nearly in line with each other. Now when it is desired to lower the plow from the position shown in Fig. 5 to the position shown in Fig. 4, then the operation is as follows: Foot-pressure is applied to the lever Q in a forward direction, thereby disengaging the locking elements o and o' from each other without communicating any positive downward force or pressure upon the plow-beam. As soon as the locking elements become disengaged from each other, the weight of the plow itself is then sufficient to carry it down to the ground, the lifting action of the spring on the plow being overcome or counteracted by the foot-pressure on the lever Q . When the plow reaches the ground, the lost motion connection between the two sleeves O and P then permits an independent adjustment or movement on the part of the sleeve O , and in this way the arm o^4 is adjusted upward sufficiently to bring the pivotal point o^7 above the axis of the two foot- 130

levers—that is to say, just above the center of the land-side axle—thereby permitting the spring to exert its pull or tension along a line above the axis about which the two foot-levers swing; and the spring having thus been adjusted to serve in its capacity of depressing the plow, the plow is then forced to its lowermost position by the combined action of the spring and the pressure on the foot-lever Q, although it is obvious that the spring is then amply sufficient to put the plow in the ground. In this way, as stated, the spring, by reason of the separate mountings for the two foot-levers, is capable of assisting in both raising and depressing the plow, and is capable of yieldingly maintaining the plow in the ground; and thus the construction not only enables the plow to operate as a stone dodger, but also enables the spring to automatically effect a quick or sudden increase in its leverage for assisting in lifting the plow. Again, and as stated, complete separation of the two foot-levers by mounting them on two separate sleeves, permits the device for locking the plow in its elevated position to be unlocked without communicating to the plow-beam any of the manual power or pressure necessary for accomplishing the disengagement of the two locking elements from each other.

As previously stated, the capability of the plow to dodge or automatically rise over obstructions is preferably obtained by so adjusting the stop n^2 that the joint or pivotal connection n^3 remains, even when the plow is down, slightly above the center, or slightly above a line drawn from the pivotal point n^4 through the center of the land-side axle. Thus the joint connection provided between the plow-beam and the land-side axle is always in readiness to buckle or break-joint upwardly against the pull or tension of the spring whenever the plow strikes an obstruction, and in so yielding to preclude all possibility of the breakage or other danger which results when the plow is rigidly and unyieldingly locked in the ground.

The combined lifting and depressing spring R, by reason of the separate mounting of the two foot-levers, is adapted to be shifted from lifting to depressing position by movement of the depressing foot-lever Q independently of the other foot-lever. Also, as has been explained, the spring travels from depressing position to lifting position—that is to say, it shifts at least part of the way from depressing to lifting position, by reason of the movement or adjustment of the depressing lever independently of the lifting lever. In other words, the shifting of the spring from lifting to depressing position, and vice versa, is accomplished through or accompanied by movement of the depressing lever independently of the lifting lever.

The object and function of the lost-motion

connection provided between the separately mounted portions of the two foot-levers, is simply this: The combined lifting and depressing spring can be shifted from a lifting to a depressing position, and vice versa, through the medium of a certain amount of adjustment or movement on the part of the depressing lever independently of the other lever, and without communicating any power or motion to the plow through the toggle-like or other jointed connection; and, further, this lost-motion connection permits of a downward adjustment or movement on the part of the locking element, which is rigid with the depressing lever, before any power or motion is communicated to the plow through the said toggle-like connection; but the shifting of the combined lifting and depressing spring, so that it will pull either above or below the center, as it may be desired to depress or lift the plow, is the principal object or function of the lost-motion connection; for while its provision makes it somewhat easier to unlock the plow, it is obvious that the locking arrangement would be operative without the provision of any relative movement whatever between the two foot-levers.

With the provision of the combined lifting and depressing spring, the depressing lever is not necessarily a depressing device in the sense of permitting the plow to be manually pushed into the ground, as the function of the lever is merely to shift the spring, and lower its rigid locking element out of engagement with the lug on the plow-beam, the spring and toggle constituting the means for pushing down on the plow as the plow-point catches and enters the ground; and, furthermore, by having the common axis of the lever stationary, I find the arrangement is more satisfactory, as the relation of the levers to the driver's position does not change materially, at least as far as convenience of operation is concerned.

What I claim as my invention is:

1. A wheeled plow comprising a body-frame, supporting wheels, a movably supported plow and beam, a pair of separately mounted foot-levers, one for lifting and the other for depressing the plow, each lever being adapted for some movement independently of and without moving the other, and a jointed connection between one of said levers and said plow beam, the two foot-levers being associated and axially aligned, whereby a portion rigid with one of said levers constitutes medium of connection through which motion is communicated from the other lever to the plow.

2. A wheeled plow comprising a body-frame, supporting wheels, a plow and beam, a pair of separately mounted foot-levers, one for lifting and the other for depressing the plow, a jointed connection between one of

said levers and the plow-beam, and a lost-motion connection between the mounted portions of said levers, whereby one of said levers is adapted for some movement without communicating pressure or motion to the said jointed connection, the two foot-levers being associated together and axially alined, whereby a portion rigid with one of said levers constitutes medium of connection through which motion is communicated from the other lever to the plow.

3. A wheeled plow comprising a body-frame, supporting wheels, a plow and beam, a pair of separately mounted foot-levers, one for lifting and the other for depressing the plow, each lever being adapted for some movement independently of and without moving the other, a jointed connection between one of said levers and the plow beam, and a combined lifting and depressing spring connected to exert its tension on a portion rigid with one of said levers, said spring being adapted to be shifted to pull either above or below the axis of the levers by the adjustment of one lever independently of the other, said levers being axially alined and having portions constituting medium of lost-motion connection through which the power of said spring is communicated to the plow.

30 4. A wheeled plow comprising a body-frame, supporting wheels, a plow and beam, a pair of foot-levers, one for lifting and the other for depressing the plow, each lever mounted for some movement independently of the other, and a toggle connection between one of said levers and the plow beam, the two foot-levers being associated together and axially alined, whereby a portion rigid with one of said levers constitutes medium of connection through which motion is communicated from the other lever to the plow.

5. A wheeled plow comprising a body-frame, supporting wheels, a plow and beam, a pair of foot-levers, one for lifting and the other for depressing the plow, each lever mounted for some movement independently of the other, a jointed connection between one of said levers and the plow beam, and a locking device adapted to lock the plow in an elevated position, said locking device being adapted to be unlocked by the adjustment of one lever independently of the other, whereby said device is unlocked without communicating pressure or power to the plow through said jointed connection, the two foot-levers being associated together and axially alined, whereby a portion rigid with one of said levers constitutes medium of connection through which motion is communicated from the other lever to the plow.

6. A wheeled plow comprising a plow and beam, supporting wheels, a pair of suitably mounted foot-levers, one for lifting and the other for depressing the plow, each lever adapted for some movement independently

of the other, a connection between one of said levers and the plow beam, and a combined lifting and depressing spring connected and arranged to be adjusted from its lifting to a depressing position, and vice versa, by an adjustment of one lever independently of the other, said levers being axially alined and having portions constituting medium of lost-motion connection through which the power of said spring is communicated to the plow.

7. A wheeled plow comprising a body-frame, supporting wheels, a plow and beam, bails connecting the body-frame with the plow beam, a lifting foot-lever and a depressing foot-lever, each lever being mounted for some movement independently of the other, a toggle connection between the lifting foot-lever and the plow beam, a locking device adapted to lock the plow in elevated position, said locking device being adapted to be unlocked by foot-pressure on the depressing lever, and a combined lifting and depressing spring connected between the body-frame and an arm rigid with the depressing lever, said spring being adapted to be shifted from lifting to depressing position, and vice versa, by movement of the depressing lever independently of the lifting lever, the two foot-levers being associated together and axially alined, whereby a portion rigid with the lifting foot-lever constitutes medium of connection through which motion is communicated from the depressing foot-lever to the plow, and said portion and another portion rigid with the depressing lever constitute lost-motion connection through which the power of said spring is communicated to the plow.

8. A wheeled plow comprising a body-frame, supporting wheels, a plow and beam, a lifting and a depressing lever, each lever mounted for some movement independently of the other, a jointed connection between the lifting lever and the plow beam, and a locking device for locking the plow in an elevated position, said device comprising a pair of mutually engaging elements rigid respectively with the plow beam and the depressing lever, the lifting lever being rigid with a portion through which motion is communicated from the depressing lever to the plow.

9. A wheeled plow comprising a plow and beam, supporting wheels, a body-frame, a toggle connection between the body-frame and the plow beam, a depressing lever and a lifting lever, a lost-motion connection between the mounted portions of the two levers, a combined lifting and depressing spring connected between the body-frame and an arm rigid with the depressing lever, and a stop device adapted to prevent the joint of the said toggle connection from moving below the center when the plow is lowered, whereby said spring yieldingly holds the plow in the ground, and the latter is capable of rising over obstructions, the lifting lever

being rigid with a portion constituting medium of connection through which motion is communicated from the depressing lever to the plow, and mutually engaging portions 5 rigid with the two levers and constituting lost-motion connection through which the power of said spring is communicated to the plow.

10. A wheeled plow comprising a body-frame, supporting wheels, a plow and beam, a lifting foot-lever and a depressing foot-lever, a toggle connection between the lifting lever and the plow-beam, said toggle connection being connected with the plow beam 15 through the medium of a plate adjustable longitudinally of the plow beam, and a locking device adapted for locking the plow in an elevated position, said locking device being adapted to be unlocked by foot-pressure on 20 the depressing lever.

11. A wheeled plow comprising a body-frame, supporting wheels, a plow and beam, bails connecting the plow beam with the body-frame, and a toggle connection be- 25 tween the body-frame and the plow beam, said toggle connection being attached to the plow beam through the medium of a plate adjustable longitudinally of the plow beam.

12. A wheeled plow comprising a plow and 30 beam, supporting wheels, a land-side axle, a pair of sleeves mounted on said axle, each adapted for some movement independently of the other, a lifting foot-lever rigid with one of said sleeves, a depressing foot-lever rigid 35 with the other of said sleeves, a toggle connection between the plow beam and the sleeve rigid with the lifting lever, and a locking device for locking the plow in an elevated position, said locking device comprising mutually 40 engaging elements rigid respectively with the plow beam and the sleeve which is rigid with the depressing lever.

13. A wheeled plow comprising a plow and beam, supporting wheels, a land-side axle, a 45 pair of sleeves mounted on said axle and adapted for some movement independently of each other, a lifting foot-lever rigid with one of said sleeves, a depressing foot-lever rigid with the other of said sleeves, a toggle 50 connection between the plow beam and the sleeve rigid with the lifting lever, and a combined lifting and depressing spring adapted to be shifted from lifting to depressing position, and vice versa, by movement of the depressing lever independently of the other lever.

14. A wheeled plow comprising a body-frame, supporting wheels, a plow and beam, a land-side axle for one of said wheels, two 55 sleeves mounted on said axle, a lifting foot-lever on one sleeve and a depressing foot-lever on the other sleeve, a lost-motion connection between the two foot-levers thus separately mounted, a locking device for locking the 65 plow in an elevated position, said locking de-

vice including a locking element rigid with the depressing lever, a combined lifting and depressing spring connected between the body-frame and a portion rigid with said depressing lever, and a hand-lever secured to 70 said axle, the foot-levers being mounted between the land-side wheel and said hand-lever, and said hand-lever being adapted for rocking said land-side axle.

15. A wheeled plow comprising a body-frame, a plow and beam, supporting wheels, a pair of separately mounted foot-levers suitably connected for lifting and depressing said plow, a land-side axle upon which said foot-levers are supported, and a hand-lever secured to said axle, the foot-levers being mounted between the land-side wheel and said hand-lever, and said hand-lever being adapted for rocking said land-side axle.

16. The improved wheeled plow comprising 85 separately mounted lifting and depressing foot-levers, each mounted for some movement independently of the other, and the fulcrumed portion of one lever being rigid with a portion constituting medium of connection 90 through which motion is communicated from the other lever to the plow.

17. A wheeled plow comprising a plow and beam, supporting wheels, means for raising and lowering the plow relatively to the 95 wheels, said means including a spring, including also pivotal connection whereby said spring yieldingly holds the plow in the ground, but whereby a slight upward movement on the part of the plow is sufficient to enable said spring to exert its tension in lifting the plow, and a manually operated toggle connection through which both spring and manual power are communicated to said beam for lifting and lowering the plow.

18. A wheeled plow comprising a plow and beam, supporting wheels, means for raising and lowering the plow relatively to the 100 wheels, said means including a lifting spring, and including also means whereby the spring 105 yieldingly holds the plow in the ground, and a manually operated toggle connection through which both spring and manual power are communicated to said beam for lifting and lowering the plow.

19. A wheeled plow comprising a plow and beam, supporting wheels, means for raising and lowering the plow relatively to the 110 wheels, said means including a lifting spring, and including also a lifting and a depressing 115 foot-lever with a lost-motion connection between them, the spring being connected with and operated by the depressing lever, whereby said spring is adapted also to act through said lost motion connection to yieldingly hold 120 the plow in the ground.

20. A wheeled plow comprising a plow and beam, supporting wheels, means for raising and lowering the plow relatively to the 125 wheels, said means including a spring, and 130

including also a lifting and a depressing foot-lever with a lost-motion connection between them, the spring being connected with the depressing foot-lever, and there being connection between the lifting lever and the beam, whereby said spring yieldingly holds the plow in the ground, but whereby a slight upward movement on the part of the plow is sufficient to enable said spring to exert its tension through said lost-motion connection to lift the plow.

21. A wheeled plow comprising a plow and beam, supporting wheels, means for raising and lowering the plow relatively to the wheels, said means including a lifting spring, and including also a lifting and a depressing foot-lever with a lost-motion connection between them, the spring being connected with and operated by the depressing lever, whereby the spring is adapted also to act through said lost motion connection to yieldingly hold the plow in the ground, and whereby a portion rigid with the lifting lever constitutes medium of connection through which motion is communicated from the depressing lever to the plow.

22. A wheeled plow comprising a plow and beam, suitable supporting wheels, a depressing foot-lever and a lifting foot-lever with a lost-motion connection between them, suitable connection between the lifting lever and the beam, and a combined lifting and depressing spring suitably connected with the depressing lever, the said lost-motion connection between the two levers also constituting medium of lost-motion connection between the depressing lever and the plow, between the lifting lever and the spring, and between the spring and the plow.

23. A wheeled plow comprising a plow and beam, suitable supporting wheels, a pair of separately mounted and axially alined levers, a lost-motion connection between the two levers, and a portion rigid with one lever and constituting medium of connection through which either lever may act on the beam.

24. A wheeled plow comprising a plow and beam, a wheeled body-frame, a pair of separately mounted and axially alined foot levers, one for lifting and the other for depressing the plow, a lost-motion connection between the two levers, and a portion rigid with the lifting lever and constituting medium of connection through which either lever may act on the beam.

25. A wheeled plow comprising a plow and beam, a wheeled body-frame, a pair of separately mounted and axially alined levers, one for lifting and the other for depressing the plow, a lost-motion connection between the two levers, and an arm rigid with the lifting lever and suitably connected with the beam, whereby said arm constitutes medium of

connection through which either lever may act on the beam.

26. A wheeled plow comprising a plow and a beam, suitable supporting wheels, and means for raising and lowering the plow relatively to the wheels, said means including a combined lifting and depressing spring having a lost-motion connection with the beam, together with means for operating said lost-motion connection and shifting the spring from lifting to depressing position, and vice versa, for the purposes set forth.

27. A wheeled plow comprising a plow and beam, a wheeled body-frame, and means for raising and lowering the plow relatively to the wheels and body-frame, said means including a combined lifting and depressing spring, together with axially alined and mutually engaging members constituting medium of lost-motion connection between the spring and the beam.

28. In a wheeled plow, the combination of a supporting frame and wheels, a plow beam and means for hanging it to the frame, a toggle comprising a pair of links pivoted together and inclining downwardly and forwardly, the lower end of the toggle being pivotally attached to the beam and the upper end being pivotally attached to the frame and the toggle being provided with means for preventing it from locking, a lever for depressing or opening the toggle and a lever for breaking it upwardly to assist in raising the plow, and spring-actuated means acting directly through the medium of the toggle to both depress and to raise the plow.

29. A wheeled plow comprising land-side and furrow wheels, and a toggle device through which both spring and manual power are communicated to the said plow for the purpose of raising and lowering the same relative to the said wheels, substantially as described.

30. A wheeled plow comprising a toggle device constituting a medium of both spring and manual power transmission, for the purposes specified, substantially as described.

31. In a wheeled plow, the combination of a plow, a toggle-joint connection, means for communicating manual lifting power through said toggle-joint to said plow, and means for communicating spring lifting power through said connection to said plow.

32. In a wheeled plow, the combination of a plow, swinging bails for supporting the plow, a toggle-joint connection, and means for communicating spring lifting power through said toggle-joint to said plow.

33. In a wheeled plow, the combination of a plow, a lost-motion connection, and means for communicating spring lifting power through said connection to said plow.

34. In a wheeled plow, the combination of a plow, a lost-motion connection, means for

communicating spring lifting power through said connection to the plow, and means for communicating manual lowering power through said connection to the plow.

35. In a wheeled plow, the combination of 5 wheels, a plow, a toggle-joint connection, a plurality of levers, a spring, means for communicating manual power from said levers through said toggle-joint to said plow, and 10 means for communicating the power of said spring through said toggle-joint to said plow, for the purposes set forth.

36. In a wheeled plow, the combination of 15 wheels, a plow, a lost-motion connection, a plurality of levers, a spring, means for communicating manual power from one of said levers through said lost-motion connection to said plow, and means for communicating the power of said spring through the said lost- 20 motion connection to said plow, for the purposes set forth.

37. In a wheeled plow, the combination of an implement, wheels supporting said implement, means for controlling the forward 25 wheels, a toggle-joint connection, means for communicating manual lifting power through said toggle-joint to said implement, and means for communicating spring lifting power through said toggle-joint to said im- 30 plement.

38. A wheeled plow comprising a frame, a plow and beam, bracket portions rigidly secured to the frame, a cylindric member mounted in said bracket portions, a pair of

foot-levers axially alined on said cylindric 35 member, one for depressing and the other for lifting the plow, means for movably supporting the plow and beam on the frame, wheels for said frame, and a toggle connection between said levers and the plow beam. 40

39. A wheeled plow comprising a frame, a plow and beam, supporting wheels, means for movably supporting the plow and beam on the frame, a pair of axially alined foot-levers, one for lifting and the other for depressing the plow, and a toggle connection 45 between said levers and the plow beam, the common axis of said levers being stationary relatively to the said frame.

40. A wheeled plow comprising a frame, 50 wheels for said frame, a plow and beam, means for movably supporting the plow and beam on the frame, bracket portions rigidly mounted on the frame, a cylindric member mounted in said bracket portions, a pair of 55 foot-levers, one for lifting and the other for depressing the plow, each foot-lever having a portion encircling or bearing on said cylindric member, and a toggle connection between said levers and the plow beam. 60

Signed by me at Rock Island, Rock Island county, Illinois, this 27th day of November, 1903.

ALBERT B. FRENIER.
